R. S. WILBUR.
HOWLER CIRCUITS FOR TELEPHONE LINES.
APPLICATION FILED MAR. 18, 1915.

1,279,808.

Patented Sept. 24, 1918.

UNITED STATES PATENT OFFICE.

RAY SETH WILBUR, OF JERSEY CITY, NEW JERSEY, ASSIGNOR, BY MESNE ASSIGNMENTS, TO WESTERN ELECTRIC COMPANY, INCORPORATED, A CORPORATION OF NEW YORK.

HOWLER-CIRCUITS FOR TELEPHONE-LINES.

1,279,808.

Specification of Letters Patent. Patented Sept. 24, 1918.

Application filed March 18, 1915. Serial No. 15,240.

To all whom it may concern:

Be it known that I, RAY SETH WILBUR, a citizen of the United States, residing at Jersey City, in the county of Hudson and State 5 of New Jersey, have invented certain new and useful Improvements in Howler-Circuits for Telephone-Lines, of which the following is a full, clear, concise, and exact description.

10 This invention relates to howler circuits for telephone lines, and has for its object the provision of means for facilitating the giving of certain notification whereby a signal having a graduated volume may be 15 placed upon a telephone line.

In accordance with the general features of this invention, means are provided for connecting with any telephone line in which the receiver has been inadvertently left from 20 the hook, a howler tone of graduated volume. The aforesaid means includes an inductorium having its secondary divided into sections, means for connecting said secondary with a telephone line, and means for 25 varying the number of effective sections of said secondary after said secondary has been connected with said line. The present invention is an improvement over that disclosed and claimed in the copending con-

30 tinuing application of George W. Kuhn, Serial No. 188,346, filed August 27, 1917.

The accompanying drawing illustrates diagrammatically one of the arrangements by which this invention may be effectuated.

35 The apparatus shown in the drawing comprises a subscriber's station A connected by means of line wires 1 and 2 to a line jack 3, located at a central office. Included in the line circuit is a cut-off relay 6 and a line relay 4, the latter of which controls the 40 circuit of a line lamp 5. For connecting the howler tone to the subscriber's line there is provided an ordinary switchboard plug 7, having associated therewith a special circuit which will be hereinafter described.

45 One of the plugs 7 and its associate circuit may be provided for each operator's position, or several of the plugs may be installed at the wire chief's board or upon a hospital board, depending upon the convenience and circumstances of a given case. An interrupter 8 connected to a source of current 9 is inductively connected by means of a transformer 10, having a primary winding 15 and 50 a secondary winding 16, to a plurality of

contacts 11, 11, radially disposed with respect to a revolving contact arm or member 12. At the center or hub of the revolving member 12 are two oppositely disposed cams 13, 13 which control a contact 14. Any means may be employed to rotate the contact member 12, such as a clockwork mechanism, or it may be attached to the shaft of a motor, and the same motor may be used to operate the interrupter 8, it being only intended to illustrate herein the respective positions of these elements in the circuits effected thereby. The interrupted current induced through the transformer 10 produces the howler tone which is applied to the subscriber's line whenever the receiver has been inadvertently left off the switchhook. The volume of this tone may be graduated so that it will gradually increase from zero or a faint quality to a maximum volume and be kept at this volume for a more or less extended period, and then dropping abruptly or gradually decreasing until it reached a zero or minimum value. It is preferred to leave some of the contacts 11, 11 vacant so that the howler tone may be completely removed from the subscriber's line for a definite interval to accomplish an object hereinafter set forth in detail.

55 A second transformer such as a repeating coil 17, having a primary winding 18 and a secondary winding 19 is inserted in the circuit of the howler tone. A condenser 20 provided in the circuit of the secondary winding 19, affords a low resistance path for the howler current when applied to the subscriber's line, thereby preventing said current from being reduced by the windings 21 and 22 of a relay 23 which functions to automatically connect the howler current to 60 the subscriber's line upon the insertion of the plug 7. Again, if it were not for the condenser 20, the windings 21 and 22 being included in the circuit of the secondary winding 19, the relay 23 might chatter by 65 reason of the alternating current induced in said secondary winding 19.

70 A lamp 58, having its circuit controlled by the relay 34 is provided for informing the operator when the subscriber has replaced the receiver upon the switchhook, after having her attention attracted by the application of the howler tone to his line.

75 The operation of the apparatus embodying the features of this invention may be de-

scribed as follows: Assume that the receiver at the substation A has been inadvertently left off the switchhook. Through the energization of the line relay 4, the line lamp 5 would be "permanent" at some point on the switchboard. The operator upon failure to receive any response when challenging the subscriber's attention, would then insert the plug 7 (assuming that each operator's position is provided with one of these plugs) into the line jack 3. This act on the part of the operator would complete the following circuit: battery 39, coil of relay 38, conductor 37, contact 36, conductor 35, winding of the relay 34, conductors 33, 32, sleeve side of the plug 7 and jack 3 respectively, conductor 31, coil of relay 6, to ground. Upon the closure of this circuit the relays 34 and 38 are actuated, the latter of which, in pulling up its armatures, closes a contact 60 which establishes the following circuit for the interrupter 8: battery 9, primary winding 15 of the transformer 10, conductor 59, contact 60, conductor 61, interrupter 8, to ground. If at this time the cam 13 of the contact member 12 happened to be engaging the resilient member 41, the contact 14 will thereby be closed, which completes the following circuit: battery 40, member 41, contact 14, conductor 42, contact 43, conductor 44, winding 21 of relay 23, to ground, thus causing the relay 23 to be actuated. The energization of the relay 23 closes contacts 24, 25 and 26, and opens the contact 36, thereby altering previous circuit conditions in the following manner: The opening of the contact 36 and closing of the contact 24 causes the deenergization of the relay 34, and the establishment of a circuit for the relay 28, which circuit may be traced as follows: battery 39, coil of relay 38, conductor 37, contact 24, conductor 27, the winding of relay 28, conductors 29, 32, sleeve side of the plug 7 and jack 3 respectively, conductor 31, coil of relay 6, to ground. The actuation of relay 28 closes contacts 30 and 55, thereby connecting relay 23 in the subscriber's line circuit which may be traced as follows: battery 45, winding 22 of relay 23, conductor 47, contact 30, conductor 49, secondary winding 19 of the repeating coil 17, conductor 50, contact 25, conductor 51, line wire 2, through the substation A and back over line wire 1, conductor 52, contact 26, conductor 53, secondary winding 19, conductor 54, contact 55, conductor 56, winding 21 of relay 23, to ground. It will be noted that the energization of the relay 23 is now dependent upon the receiver at the substation A being removed from the switchhook. The quality of the howler tone which is sent out to the subscriber's station as the contact member 12 engages the contacts 11, 11, will depend upon which one of the arrangements hereinbefore described is employed.

It will be noted that the contact 14 is opened upon the disengagement of the cam 13 with the resilient member 41, and that before the relay 23 can be originally energized, the contact 14 must be closed. This feature prevents the application of the howler tone to a subscriber's line when said tone is at its maximum volume it being inoperative unless the howler tone is faint or has temporarily been completely removed. It will also be noted that upon the energization of the relay 23, through the opening of the contact 36, the relay 34 is deenergized, thereby extinguishing the lamp 58 whose circuit is controlled by the relay 34.

When the receiver at the substation A is replaced upon the switchhook the energizing circuit for the relay 23 is interrupted and the deenergization of this relay is insured by the contact member 12 engaging some of the contacts 11, 11 left vacant. These vacant contacts preclude any possibility of the current induced through the secondary winding 19 of the repeating coil 17 from maintaining the relay 23 in an operative position upon the replacement of the receiver at the substation. By the deenergization of the relay 23, the contact 36 is again closed, thereby reestablishing the circuit for the relay 34 described above. The actuation of the relay 34 closes the contact 57, thereby completing a circuit through the lamp 58 from the battery 56. The relay 34 is preferably of the type slow in releasing, so that in event the subscriber at substation A worked his receiver hook up and down to attract the attention of the operator, the lamp 58 would not be flashed by the interruption of its circuit upon the energization and deenergization of the relay 34 caused by the subscriber's action.

From the above it will be apparent that by the means provided in this invention a howler tone may be applied to a subscriber's line on which the receiver has been inadvertently removed, without incurring the danger of applying a howler tone of considerable volume to the subscriber's line at a time when the subscriber may happen to have the receiver to his ear.

What is claimed is:

1. In a telephone exchange system, a telephone line, a tone producing means including an inductorium having its secondary divided into sections, and means for automatically and variably associating said secondary sections with said line.

2. In a telephone exchange system, a telephone line, a tone producing means including an inductorium having the secondary divided into sections, means for associating said secondary with said line, and means for increasing the number of effective sections of said secondary after said secondary has been connected to said line.

3. In a telephone exchange system, a telephone line, an auxiliary circuit, switching means for connecting said auxiliary circuit with said telephone line, a tone producing circuit including an inductorium primary controlled by connection of said auxiliary circuit with said telephone line, an inductorium secondary divided into sections, means for associating said secondary with 5 said line, and means for increasing the number of effective sections of said secondary after said secondary has been connected to said line.

4. In a telephone exchange system, a telephone line, an auxiliary circuit, switching means for connecting said auxiliary circuit with said telephone line, a tone producing circuit including an inductorium primary controlled by connection of said auxiliary 10 circuit with said telephone line, an inductorium secondary divided into sections, a circuit and connections for associating said secondary with said telephone line, and means for increasing the number of effective 15 sections of said secondary after said secondary has been connected to said line.

5. In a telephone exchange system, a telephone line, an auxiliary circuit, switching means for connecting said auxiliary circuit 20 with said telephone line, a tone producing circuit including an inductorium primary controlled by connection of said auxiliary circuit with said telephone line, an inductorium secondary divided into sections, contact members to which the separate sections 25 of said secondary are connected, a rotatable arm adapted to wipe over said contacts to gradually increase the number of effective

sections of said secondary, a circuit and connections for associating said secondary with 40 said telephone line, a contact closed by said rotatable arm in its normal position, and switching means controlled by the connection of said auxiliary circuit with said line and by said contact for closing the circuit 45 for associating said secondary with said telephone line.

6. In a telephone exchange system, a telephone line, an inductorium having its secondary divided into sections, fixed contacts 50 to which the secondary sections are joined, a source of intermittent current in circuit with the primary of the inductorium, means for connecting the secondary with the telephone line, and a brush traveling over the 55 fixed contacts to vary the number of secondary sections in circuit thereby to vary the strength of current traversing the telephone line.

7. In a telephone exchange system, a telephone line, a source of intermittent current, sectional controlling means traversed by such current, means for inductively associating the sectional controlling means with the telephone line, and a traveling member for 60 varying the number of controlling sections in circuit with the source of current and for rendering successive controlling sections 65 active, thereby to vary the strength of current traversing the line. 70

In witness whereof, I hereunto subscribe my name this 16th day of March A. D., 1915.

RAY SETH WILBUR.
